US00D600671S

(12) **United States Design Patent**
Akatsu et al.

(10) **Patent No.:** US D600,671 S
(45) **Date of Patent:** ** Sep. 22, 2009

(54) **TELEPHONE**

(75) Inventors: **Masafuku Akatsu**, Kawasaki (JP); **Eiichi Taniguchi**, Kawasaki (JP); **Tadamine Toh**, Kawasaki (JP); **Masaki Kobayashi**, Kawasaki (JP); **Takaaki Fujii**, Kawasaki (JP); **Masaru Kunii**, Kawasaki (JP); **Jun Tamatsu**, Kawasaki (JP); **Fumiyo Yoshi Toyoshima**, Kawasaki (JP); **Naoki Mori**, Kawasaki (JP); **Noriaki Nozaki**, Kawasaki (JP); **Hirosi Kamezawa**, Kawasaki (JP); **Toshiki Takeda**, Tokyo (JP)

(73) Assignee: **NEC Infrontia Corporation**, Kawasaki-shi (JP)

(**) Term: **14 Years**

(21) Appl. No.: **29/334,396**

(22) Filed: **Mar. 25, 2009**

(57) **CLAIM**

The ornamental design for a telephone, as shown and described.

DESCRIPTION

FIG. 1 is a front, right side, bottom perspective view of a telephone;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a front elevational view thereof showing a state in which the handset is removed from the base of the telephone; and,

FIG. 9 is a right side view thereof in which a leg and the display unit are each shown in an alternate position.
